UNITED STATES PATENT OFFICE.

ROBAH J. BINKLEY, OF POMONA, AND ROBERT A. STEPS, OF LOS ANGELES, CALIFORNIA.

BEET-CUTTER.

1,241,702.

Specification of Letters Patent.

Patented Oct. 2, 1917.

Application filed April 6, 1917. Serial No. 160,126.

To all whom it may concern:

Be it known that we, ROBAH J. BINKLEY and ROBERT A. STEPS, citizens of the United States, respectively residing at Pomona, in the county of Los Angeles and State of California, and at Los Angeles, in the county of Los Angeles and State of California, have invented a new and useful Beet-Cutter, of which the following is a specification.

The drum type beet slicer, to which this invention relates, is a very old and well known class of machinery, and is characterized by the fact that the knives are carried on the internal periphery of a cylindrical drum revolving on a horizontal axis, the beets being fed into the drum through a suitable hopper, and the shreds or cuttings passing out through suitable openings adjacent the knives; also a stationary apron is usually fastened in the drum on the trailing side, and its lower face is so formed that the beets are wedged and pressed onto the knives.

These cutters are used in beet sugar mills for cutting beets into shreds prior to diffusion, and the following are some improvements embraced in our invention.

First:—the cutting capacity of these cutters is increased without increasing their dimensions or speed. This is accomplished by the novel spider described herein.

Second:—by means of the corrugated guide bars long V shreds are uniformly produced without effecting any lateral adjustment of the knife blocks, and the result is much more satisfactory than where such adjustment is used for the purpose.

Third:—rocks can be automatically discharged from the cutter while running without the trouble incident to removing a cylindrical rock catcher from the machine.

Fourth:—the knife blocks used in these cutters are improved.

Other features of invention will appear from a consideration of the claims and specifications.

The accompanying drawings illustrate one form of the invention. Figure 1, is a plan section of the cutter; Fig. 2, is a transverse section of same; Fig. 3, is a transverse view of the cutter in full; Figs. 4, and 5, show the improved spider; Fig. 6, is an enlarged view showing a detail; Fig. 7, is an enlarged

view showing the spider arm; Fig. 8, is a transverse section of the knife block, the section being on broken line X⁸—X⁸ Fig. 9; Fig. 9, is a plan view of the knife block; Fig. 10, is a view of the corrugated guide bar in relation to a corrugated knife; Fig. 11, illustrates the shreds that are uniformly cut in this cutter; Fig. 12, illustrates shreds of odd shapes cut prior to the advent of the corrugated bar; Fig. 13, is a sectional view of a knife block the section being on line X¹³—X¹³ Figs. 8, and 9,—this view shows in detail the mechanism for adjusting the guide bars; Figs. 14, 15, and 16, are respectively side, end, and top views of the wedge used in adjusting the bars; Fig. 17, shows the spider arm with a good form of wear plate thereon; Fig. 18, shows a longitudinal section through the wear plate.

Broadly speaking the cutter consists of a revoluble drum operating in a stationary casing. The principal parts which make up the cylindrical drum are the shaft 1, the heavy circular disk 2, the spider 3, and the knife blocks 4; while the parts that make up the stationary casing are the side members 6, and 7, the base 8, a properly formed apron and chute 9, the cover plate 10, and the bearings 11, and 12. The general relation of these parts appears in Figs. 1, 2, and 3.

In Fig. 2, some of the knife blocks are shown in section, and in these the cutter knives 13, can be seen along the internal periphery of the drum. These knives are acting on the beets.

It will be understood that on one side the revolving drum is closed by the disk 2, and that the drum is closed all around its periphery by the knife blocks and spider. However, so far as the revoluble parts are concerned, the drum is open on the side opposite disk 2, but the stationary side member 6, see Figs. 1, and 3, closes the drum here, except at the opening 14 adjacent the hopper 15, through which the beets are fed into the revolving drum.

Fig. 2, shows the beets in the drum, and as the latter rotates in the direction of the arrow, the knives 13 cut off shreds which pass out through the knife blocks, then down through base 8 into a suitable conveyor or spout not illustrated in the figures. As the operation proceeds the beets are urged under

the apron 9, and on account of the tapered relation between this member and the face of the drum, the beets are pressed hard onto the knives, and the cutting proceeds with 5 good effect.

In some mills where the beets are gathered from rocky country, or where inadequate provision is made, rocks sometimes enter the cutter with the beets, and it is desirable to 10 have provision for coping with this situation, as the rocks might seriously damage the knives. Heretofore it was attempted to trap the rocks in a cylinder carried in apron 9, but this was usually unsatisfactory. The 15 idea was that on trapping the rock in the cylinder the cutter should be stopped, the cylinder withdrawn, and after removing the rocks and debris therefrom, the cylinder was to be replaced in the cutter, and operations 20 resumed. For various reasons these cylinders were troublesome. For instance, if they were left open during normal operation, the beets rushed in and filled them the instant the cutter started, or if they were 25 left closed during normal operation, and opened when a rock was heard, the beets again rushed in and filled them before the rock got to it. In either event the cylinder was usually packed before the rock could 30 enter, and there was little or no room for the rock when it got there, in consequence of which the rock was usually held on the knives the same as though no cylinder were present. Obviously the knives suffered ac- 35 cordingly. Again after the cutter was stopped and the operator desired to get the rock, it was often very difficult to remove the cylinder from the cutter, because of the manner in which the beets locked the cylinder in place. Some beets would be half in 40 and half out of the cylinder, so that the latter was locked and could not be withdrawn except with great effort and delay. It will be noted that the cutter was idle dur- 45 ing the delay, and the efficiency of the factory was reduced accordingly.

In our cutter however, the whole situation is handled differently. The cylinder is entirely omitted and the upper portion of the 50 apron comprises a flat removable gate 15', Figs. 1, 2, and 3, and in addition, the upper portion of the apron behind the gate, is formed like a chute, the rear portion 16 being at a slightly higher elevation than the 55 forward portion 17, so that a continuous decline is formed leading from gate 15', down the chute and out through the stationary side 6 through the hole 18 which opens the entire chute at that side.

60 When the operator notices a rock in our cutter he pulls gate 15' through the stationary side 6, the handle 19, Fig. 1, on the gate, being specially formed for this purpose. When the gate is completely out the beets 65 come tumbling down the chute and auto-

matically fall out of the cutter through opening 18. The stream is continuous while the cutter continues to run, and on account of the flow of beets thus created, the rock is usually swept along the cutter and discharged with the beets before the motion of the cutter is arrested. In fact, after the rock is seen falling out of the chute there is no further necessity for slowing the cutter, and the gate 15 can be shoved back in place 70 and operations resumed immediately. In this way the rocks can often be removed without even stopping the cutter, and the annoyance, and particularly the delay, occasioned in endeavoring to remove the rock 75 with the cylindrical rock catcher is entirely eliminated. This reflects favorably upon the efficiency of the cutter as well as of the entire mill, and in order to facilitate the closing of the gate, its forward edge 20, Fig. 80 1, is beveled into a sharp edge, so that it can be cut right through the beets, if necessary.

The element 21, Fig. 2, represents a rev- 85 oluble brush used for brushing the knife edges and preventing clogging while the cutter works on woody beets. The debris brushed off by the brush falls through opening 22, onto the chute and out through opening 18, thus keeping the space about the brush free and clear. In the ordinary cutters using a cylindrical rock catcher, how- 90 ever, it is practically impossible to discharge this debris without remodeling the machine, and in the remodeling process the cylinder is usually omitted or sealed up before pro- 95 vision can be secured for conveying the brushings away from the brush. The ease with which our system accommodates itself to these requirements illustrates another ad- 100 vantage of our cutter over the type using a 105 cylindrical rock catcher.

Attention will now be diverted to the de- 110 tails of the knife blocks 4. In the first place it will be understood that each knife block holds 3 rows of knives, separated by 115 a like number of guide bars, and that the knife blocks can be removed from the machine by an opening in side member 6 not shown in the drawing. Usually the equipment of a cutter includes several sets of 120 knife blocks, the knives in one set being set up and adjusted outside of the cutter, while another set, with its knives, is operating in the cutter, and when the knives in the cutter become dull the knife blocks are pulled out and another set of blocks, with newly sharp- 125 ened knives, are shoved in. In this way the knives can be changed with only a short delay in the operation of the cutter, and the cutting capacity of the factory is thus main- tained at a high standard.

Figs. 8, 9, 10, and 13 to 16 inclusive, show our improved form of knife block.

Generally speaking knife blocks consist of two side members 23, connected by heavy 123

cross arms 24,—see particularly Fig. 8. The knives 13 are bolted to the cross arms, and in front of each knife is mounted an adjustable guide bar 25. The knives 13, it will be understood, are of an old standard type, the edge and face being corrugated as shown at 26, Figs. 6, 7, and 10, and the channels 27 project down from the bottom of each corrugation. The guide bars 25 are adjustable as to height, and obviously the thickness of the shreds depends on the height to which these bars are adjusted in relation to the knives. Also it might be stated that prior to the advent of corrugated guide bars for these cutters, the upper guiding face of the bars was usually flat, in consideration of which fact the cuttings were often irregular in length and section. This was due principally to the fact that the beets would shift and move around a little while passing from the edge of one knife to the edge of the next one. Consequently, with flat bars, odd cuttings of the character shown in Fig. 12 are quite common, and this is true regardless of the precautions taken to align all points of the knives with each other around the periphery of the cutter. This alignment is very difficult to effect, and even when accomplished is of little service because the beets shift between the knives as stated. In other cutter however, the guide bars 25 are corrugated to conform with the knives, as shown in Fig. 9, and particularly Fig. 10. The corrugations in the bars line up accurately with the corrugations in the knives, and the result is that after the beet is cut by one knife the corrugations in the next bar catch in the corrugations cut by the preceding knife and guide the beet into accurate alignment with the next knife, so that each knife will cut the beets right over the corrugations cut by the preceding knife. In this way V shaped shreds of the kind shown in Fig. 11, are uniformly cut in our cutter without the inconvenience of attempting to laterally adjust either the knives or the knife blocks.

It will be understood that these V shreds shown in Fig. 11, are far more preferable than those shown in Fig. 12, as the sugar can be dissolved from the former much more thoroughly and with considerably less water than from the latter, and the savings thus effected by the corrugated guide bar are considerable and are fully appreciated by the trade.

In addition to corrugating our bar, its upper face 28 is convexed to sweep nicely into the knife, and in this way the beet is so guided that long V shaped shreds can be cut without breaking or bruising them as they pass from the knife. In addition to this our bars are adjusted straight up and down, and are not adjusted by rocking them in a socket, as was common heretofore.

On this account the ideal inclination between the knife and the convexed face can be maintained constant at all adjustments of the bars, whereas with the rocker bar this inclination necessarily changes with each adjustment, and the cutting of long shreds is not accomplished so well in the latter case.

We will now direct attention to the means which we adopt for adjusting the bars straight up and down, and it will be noted that this means is simpler than that shown in a co-pending application by R. J. Binkley, Serial No. 107,507, filed July 5, 1916, the last mentioned application covering the general idea of raising and lowering of the bar straight up and down.

The simplified means used in this invention for accomplishing the same result, can be described as follows:—Fig. 8 shows the cross arms 24 which carry the knives 13 on their forward portion, and the bars 25 on their rearward portion. At the rear these arms have a portion 29 which may run at an inclination across the box as shown in Fig. 13. On the upper face 30 of this portion runs the long wedge 31, see Figs. 8, 9, and 13 to 16, inclusive. The upper face 32 of this wedge may be horizontal and carries the guide bar 25, while the lower face of the wedge is inclined in conformity with the inclination of face 30, in the cross arm 24, so that as the wedge is moved back and forth on face 30 the guide bar will of necessity be raised and lowered without changing the inclination between the guiding face 28 and the knives. Of course substantially the same result would be accomplished if the bottom of the guide bar was inclined, instead of the top of the cross arm, but all changes of this character are obvious modifications of our conception, and will be left to the judgment of the designer, except that the form described above is deemed the best for several reasons.

For the purpose of holding the wedge 31 on the cross arm portion 29, lugs 33, Figs. 8, 9, and 13, project up as shown, and for the purpose of shifting the wedge back and forth a large teat 34, see Figs. 14, 15, and 16, is cast thereon. This teat is shown dotted in Fig. 13, in order to more clearly illustrate the parts below.

Also in order to fasten the guide bar in place, after correct adjustment has been made, a heavy stud 35 is provided and projects down from the bar. This stud runs in an elongated slot 36, formed in the wedge, and a neck nut 37, Figs. 8, and 13, cooperates with this stud and locks the guide bar 25 and wedge 31 securely in place.

It might be noted also that during operation the pressure of the beets on the guide bar tends to shift the bar toward the knife. This tendency might be checked by the force of the neck nut on the stud, all faces on

wedge, bar, etc., being substantially square with each other, but in addition to this, the extra precaution has been taken of adding the heavy pins 38, Figs. 8, 9, and 13, which 5 are pressed into the sides 23 of the knife block, and project slightly inward therefrom as shown in Figs. 9, and 13. This is for the purpose of holding the corrugated guide bars back when the beets push on 10 them during operation, and illustrates one good mode of accomplishing this result. Other means will readily occur to the reader.

The foregoing practically completes the description of the knife blocks, and attention will now be directed to our improved spider which is shown particularly in Figs. 4, 5, 6, and 7. This spider may be designed with exactly the same over all dimensions as were heretofore used, but in view of the 15 improved shape of our arms 5, nine knife blocks can be carried instead of only eight as heretofore, and this despite the fact that our mounting for the blocks will be even stronger than in ordinary eight block 20 spiders. The reason for this is that heretofore the width of metal required at the arm for strength, was chiefly placed in the path of the knife blocks, and the arms were built 25 symmetrical behind this portion. It cannot be doubted that this secures the strength, but we have found that such construction is unnecessarily wasteful of space, as the 30 strength is gained at the expense of the cutting capacity of the cutter. This is because 35 the metal which produces strength was located at the inner periphery of the arm and in direct line with the knife blocks, and being so located took up room that should 40 have been used for holding additional knife blocks with their complement of knives. In our spider however, we have refashioned 45 it ingeniously and have removed some metal from the path of the knife blocks and have added it behind this point where there is 50 room for it. This new construction is fully as strong as the old one and sufficient room 55 is gained at each arm so that in the aggregate an additional knife block of standard size can be inserted in the same diameter spider. It is in this way that the nine knife blocks, with their knives, may be carried instead of only eight as heretofore, and an increase of 12½% in the cutting capacity of the machine is secured without sacrificing any strength whatever.

Obviously the same principle applies further, and in spiders of other diameters, so that still more knife blocks could be carried if desired, but the conception remains the 60 same throughout.

Attention is now directed to Fig. 7, which shows one of the approved forms of our arms.

By way of introducing it we wish to state 65 that our arms have the same cross sectional

area as those commonly used in the eight block spiders; also our arms have the same maximum dimensions both radially and transversely; in consideration of which facts it will be apparent that our arms are fully 70 as strong both in shear and torsion, as those heretofore used, and in other respects they are still stronger, as will be pointed out later. Passing by this point for the present, we wish to note that in our arm the inner 75 rectangular portion 39 drives the knife blocks, and is of more than ample strength because it is backed up by the wide rear portion 40. With reference to a medial line X'-X', Fig. 7, passing midway through 80 the driving portion 39 of the arm, it will now be noted that the rear strength giving portion 40 is unsymmetrical therewith. In this form of the arm a considerable portion of the metal is loaded on the trailing side 85 and the forward portion 41 is cut back to correspond with the bevel of the cross arm 24, which holds the knives 13,—see particularly Fig. 7. The principle of this construction is as follows:—as the knives 13 cut 90 shreds from the beets, the shreds pass back along the under face of the knives, between channels 27, until they reach the rear curved portion 42 of the knives, where the shreds are gently deflected downwardly, and the 95 forward face 43 of the cross arm, being beveled in continuation of curve 42, receives the shreds and passes them on gently without danger of breaking or bruising them. It is quite important that the shreds be not 100 broken into short pieces as long shreds give much nicer results in the diffusion processes in sugar factories than short ones do, and consequently any circumstances, such as sharp turns or corners, which would tend to 105 break the shreds, would be deemed undesirable. For this reason the advancing face 41 of our spider arm 5, is cut back as shown, and the result is beneficial with regard to the production of long shreds. On the other 110 hand the metal that is thus taken from the forward side of our arm is loaded on the trailing side as shown. A moment's consideration will also show that there is an abundance of room for the metal there because the shreds from the next succeeding 115 knife pass off considerably behind the arm. This can be seen in Fig. 2.

Of course if the designer is willing to sacrifice length of shreds, the spider arm can be 120 made symmetrical about line X'-X', and by building the integral rear portion 40, of the arm, so that it projects somewhat beyond the inner driving portion 39, both on the advancing and trailing sides of the arm as 125 shown, it is possible to secure at least the additional capacity which we have pointed out, but we deem it advisable to go further and adopt all of our recommendations by building the rear portion 40 unsymmetrical 130

around line X^7 — X^7 , instead of symmetrical, as this affords better exit for the shreds as well as greater capacity.

The next general feature in our improved 5 spider concerns itself with the manner in which we protect it against wear. In this connection it will be realized that the pressure and drag of the beets rapidly wear the inner face of the spider arms, and unless 10 provision is made for taking this up, the situation is soon rendered objectionable because the beets become exposed to sharp corners on the advancing knife blocks, and the beets are mashed into pulp by these corners, 15 instead of being cut into shreds by the knives. Also the continuous act of sliding the knife blocks in and out between the spider arms, cause the latter to wear, and consequently the knife blocks soon fit loosely 20 between the arms and tend to fall inward toward the center of the cutter. This again is undesirable because the tendency to pulp is increased.

For these reasons we provide the removable wear plates 44 and 45, respectively on the inner face and the sides of the arms, and in addition the lugs 46 are bolted to the inner face of the arms at points corresponding to the running sides 25 of the knife blocks, this 25 being seen best in Fig. 4. In this way the lugs 46 act as continuations of the sides 25 of the knife blocks. These different plates are fastened to the arms by means of screws, or other suitable fastenings, which need not 30 be illustrated. Of course when the plates become worn, even to a slight degree, they can be replaced at small cost and the spider is then kept like new. Also the pulping tendency referred to is eliminated and clean 35 cutting is insured at all times.

Figs. 17 and 18 show an improved form 40 of wear plate 47 which we recommend. The feature of this plate lies in the fact that it is integral, the single box member shown 45 taking the place of five separate pieces, namely plates 44 and 45, and lugs 46, Fig. 7. This integral wear plate is of box construction and can be easily machined. It is fastened to the spider arm by heavy screws 50 48, and if desired the channel running through the box can be made larger than the inclosed portion of the spider arm. If this 55 is done only the inner face 49 of the arm need be machined, and after bolting the finished wear plate 47 onto the arm, lead or babbitt or like material 50 can be poured between the plate and the arm and the space filled up. A special dye can be used for casting this metal in, and the process is not 60 only quicker, but also slightly cheaper, than machining the arms on the sides. Also, if proper jigs and templates are used the results are considerably more accurate. For 65 the purpose of causing the lead or babbitt to adhere to the arm, dovetailed apertures

51, or oppositely inclined holes, may be formed in the sides of the arms, and after the metal cools the portion which has run into these holes will draw the remainder tight into place.

The foregoing construction has several 70 obvious advantages chief of which are the greater strength and simplicity obtained in the wear plates, and also the greater uniformity which can be procured.

In concluding the discourse on our spider arm, we now wish to mention that line A—A, Fig. 7, indicates the direction in which 80 blows are struck upon the arms by rocks or other hard substances in the cutter, when the cutter is running, and in our spider this line represents the line of greatest strength 85 through the arms. Consequently it follows that the shape which we have contrived has the additional advantage of having its greatest strength in the direction in which the severest blows are struck, and the value of this feature is so obvious as to require no further discussion. By pointing it out we merely desire to show that in addition to increasing the cutter capacity this shape for 90 the arm also increases the strength of the spider.

Referring now to Fig. 6, this shows a detail which should be mentioned. It will be 95 understood that the various spider arms 5 are tied together by the annular ring portion 3 of the spider. Fig. 6 shows a section through this ring midway between the arms, and the section also shows one of the knife 100 blocks 4 in place. In some cutters it has been customary to merely push the knife blocks in, and then to run the cutter without fastening the blocks. Under ordinary circumstances this is usually sufficient, as 105 there is no force urging the knife blocks transversely from between the spider arms. We deem it desirable however, to make some positive provision against any possible creeping of the knife blocks out from the 110 spider arms, because should such creeping accidentally occur, the knife blocks would rub against the stationary side 6 of the cutter, and by striking some obstruction might be done. Accordingly we use a blunt shoulder screw 52 Fig. 6, carried midway between the spider arms, this screw butting on the back of the knife block as shown. In this locality the knife block is machined with the flat face 53 from which projects the 115 raised portion 54. The side 55 and the top 56 of this raised portion are perfectly square with each other and with the face 53 as shown. Also the relation between the shoulder 57, of the screw, and the faces 55 and 120 58 of the knife blocks, and the face 59 of the spider hub 2 is such that when the knife box is shoved clear in,—i. e. when face 58 butts against face 59,—then the shoulder 125 portion 57 of the screw will nicely clear the 130

face 55 on the raised portion 54 and will rest on face 53 as shown. When the screw is thus set, it is obvious that the knife block cannot creep far because the raised portion 54 soon comes against the screw and further displacement is prevented. This, it will be seen, effects a simple and convenient way of holding the knife block, and the screw 52 can be so placed that the further side of the 10 block cannot rub against the stationary side 6 of the cutter, as noted above. Also the clearance in the parts is such that when the blocks are shoved clear in till they bunk on the spider hub, the recoil is usually not so 15 great but that the flat shoulder 57 of the screw can still clear face 55 of the raised portion, and seat itself on face 53 as shown.

With respect to this screw 52, it should be noticed that same is not used for shifting 20 the boxes transversely. In fact no transverse motion of the box could be effected by means of this screw because of the manner in which we have formed and arranged it. In our construction it will be understood 25 that instead of attempting to adjust transversely the knife boxes for the purpose of alining the points of the knives around the entire periphery of the cutter, we use our corrugated guide bars as mentioned, and 30 these insure the cutting of perfect V shreds more satisfactorily than when the transverse adjustment of the knife boxes is relied on for this purpose.

This now concludes the description of our 35 invention, but it will of course be realized that many modifications of detail can be contrived.

Claims.

1. In a beet cutter, the combination of a 40 revoluble drum adapted to hold beets the axis of rotation of said drum being substantially horizontal, a stationary side member mounted beside said revoluble drum, a movable gate in said drum, and a chute leading 45 from said gate out through said stationary side member.
2. In a beet cutter the combination of a revoluble drum adapted to hold beets the axis of rotation of said drum being substantially horizontal, a stationary side member mounted beside said revoluble drum, a removable gate in said drum, and a curved chute leading down from said gate and out through said stationary side member.
3. In a beet cutter the combination of a 55 revoluble drum adapted to hold beets the axis of rotation of said drum being substantially horizontal, a stationary side member mounted beside said revoluble drum, said 60 stationary side member having an aperture therein, a removable gate adapted to slide through said aperture, said stationary side member having another aperture therein, and a chute leading from said gate through 65 the last said aperture in the side member.

4. In a beet cutter the combination of a revoluble drum adapted to hold beets the axis of rotation of said drum being substantially horizontal, a stationary side member mounted beside said drum, a curved apron 70 fastened in said drum, said side member having an aperture, a flat gate adapted to slide through said aperture into said drum, said stationary side member having another aperture therein, the upper face of the apron 75 being a curved chute leading from the gate downward, and out through the last mentioned apertures in the side member.

5. In a beet cutter the combination of a revoluble drum adapted to hold beets the 80 axis of rotation of said drum being substantially horizontal, a stationary side member mounted beside said drum, a curved apron fastened in said drum, said side member having an aperture, a flat gate adapted to 85 slide through said aperture into said drum, said side member having another aperture therein, the upper face of said apron being inclined downward from said gate and at the side farthest from said side member said 90 upper face of the apron being at a higher elevation than at the side adjacent said side member, so that beets can roll down the apron from the gate and out through the last mentioned aperture in said side member. 95

6. In a beet cutter the combination of a revoluble drum adapted to hold beets, the axis of rotation of said drum being substantially horizontal, beet knives mounted on the internal periphery of said drum; a stationary side member mounted beside said drum, said side member having an aperture therein, a stationary apron member mounted in said drum the lower face of the lower portion of said apron member being curved to 105 press the beets onto said knives, and the upper face of said lower portion of the apron member being a chute curved downward and outward with its lower portion adjacent the aperture in said side member, a web formed across the upper portion of said apron member dividing same into two compartments, a brush in the upper of said two compartments, and the lower compartment being bounded below by said chute, said web also 110 having an aperture therein located so that the debris brushed from the knives can pass from the uppermost of said compartments through the lowermost compartment and out of the cutter past the chute and aperture in 115 said side member.

7. A spider for beet cutting machines comprising a circular portion and arms projecting transversely therefrom, the said arms having an inner driving portion and an 120 outer strength giving portion, the inner driving portion being narrower circumferentially than the outer strength giving portion.

8. A spider for beet cutting machines com- 125

prising a circular portion and arms projecting transversely therefrom, the arms comprising an inner driving portion and an outer strength giving portion, the outer strength giving portion being unsymmetrical with respect to a radial line passing midway through the inner driving portion.

9. A spider for beet cutting machines comprising circular portion and arms projecting transversely therefrom, the arms comprising an inner driving portion and an outer strength giving portion, the inner driving portion being narrower circumferentially than the outer strength giving portion, and the outer strength giving portion being unsymmetrical with respect to a radial line passing midway through the inner driving portion.

10. A spider for beet cutting machines comprising a circular portion and arms projecting transversely therefrom, the arms comprising an inner driving portion and an outer strength giving portion, the inner driving portion being narrower circumferentially than the outer strength giving portion, and the outer strength giving portion being unsymmetrical with regard to a radial line passing midway through the inner driving portion, the said strength giving portion being heavier on the trailing side of the said radial line than on the forward side thereof.

11. In a beet cutting machine the combination of a spider having transverse arms, knife blocks carried between said arms, the knife blocks having cross bars, knives bolted to said cross bars, the said cross bars being beveled backward from the knives to afford easy egress for the cuttings, and the said spider arms comprising an inner driving portion and an outer strength giving portion, the outer strength giving portion being unsymmetrical with respect to a radial line passing midway through the inner strength giving portion, and the advancing side of said strength giving portion being cut backward.

12. A spider for beet cutting machines comprising a circular portion, arms projecting transversely therefrom, and removable wear plates of channel shaped section fastened to said arms.

13. A curved knife box for beet cutting machines, comprising side members and cross bars connecting said side members, a plurality of guide bars carried on the forward sides of said cross bars and a plurality of knives carried on the rear sides of said cross bars, a long wedge between the guide bar and cross bar for adjusting the height of the guide bar evenly without tilting the guide bar in any direction, a stud fastened to the guide bar and reaching down past the wedge, and a nut coöoperating with the stud for fastening the guide bar to the box.

14. A curved knife box for beet cutting

machines, comprising side members and cross bars connecting said side members, a plurality of guide bars carried on the forward sides of said cross bars and a plurality of knives carried on the rear sides of said cross bars, a long wedge between the guide bar and cross bar for adjusting the height of the guide bar evenly without tilting the guide bar in any direction, a stud fastened to said guide bar and reaching down past the wedge, the cross bar having an aperture below the guide bar for the purpose of receiving the stud, the aperture being counterbored from the lower side of said cross bar, and a nut located in said counterbored portion of the cross bar for coöoperating with said stud in fastening the guide bar to the box.

15. A curved knife box for beet cutting machines, comprising side members and cross bars connecting said side members, guide bars carried on the forward sides of said cross bars and knives carried on the rear sides of said cross bars, a long wedge between the guide bar and cross bar for adjusting the height of the guide bar evenly without tilting the guide bar in any direction, the wedge having a long slot running lengthwise thereof, a stud fastened to the guide bar and reaching down past the wedge through said slot, and a nut coöoperating with the stud for fastening the guide bar to the box.

16. A curved knife box for beet cutting machines, comprising side members and cross bars connecting said side members, guide bars carried on the forward sides of said cross bars and knives carried on the rear sides of said cross bars, a long wedge between the guide bar and cross bar for adjusting the height of the guide bar evenly without tilting the guide bar in any direction, the wedge having a long slot running lengthwise thereof, a stud fastened to the guide bar and reaching down past the wedge through said slot, the cross bar having an aperture below the guide bar for the purpose of receiving the stud, the aperture being counterbored from the lower side of the said cross bar, and a nut located in said counterbored portion of the bar for coöoperating with said stud in fastening the guide bar to the box.

17. A curved knife box for beet cutting machines, comprising side members and cross bars connecting said side members, guide bars carried on the forward sides of said cross bars and knives carried on the rear sides of said cross bars, a long wedge between the guide bar and cross bar for adjusting the height of the bar evenly without tilting the guide bar in any direction, and a slot formed on said wedge for facilitating the movement of same.

18. A curved knife box for beet cutting

machines, comprising side members and cross bars connecting said side members, guide bars carried on the forward sides of said cross bars and knives carried on the 5 rear sides of said cross bars, the face of the cross bar below the guide bar being inclined with respect to the length of the cross bar, and a long wedge between said guide bar and cross bar for adjusting the height of the 10 guide bar evenly without tilting the guide bar in any direction.

19. A curved knife box for beet cutting machines, comprising side members and cross bars connecting said side members, 15 guide bars carried on the forward sides of said cross bars and knives carried on the rear sides of said cross bars, the face of the cross bar below the guide bar being inclined with respect to the length of the cross bar, 20 a long wedge between said guide bar and cross bar for adjusting the height of the guide bar evenly without tilting the guide bar in any direction, a stud fastened to the guide bar and reaching down beyond said 25 wedge, the cross bar having an aperture below the guide bar for receiving the stud, the

aperture in the cross bar being counterbored below and a nut located in said counterbored portion of the cross bar for coöperating with said stud and fastening the guide 30 bar to the knife box.

20. A curved knife box for beet cutting machines, comprising side members and cross bars connecting said side members, guide bars carried on the forward sides of 35 said cross bars and knives carried on the rear sides of said cross bars, a long wedge between the guide bar and cross bar for adjusting the height of the guide bar evenly without tilting the guide bar in any direction, and projections extending from said side members inward and butting against the guide bars for preventing the guide bars 40 from slipping toward their corresponding knives.

In testimony whereof, we have hereunto set our hands at Los Angeles, county of Los Angeles, State of California, this 26th day of March, 1917.

ROBAH J. BINKLEY.
ROBERT A. STEPS.
